ADJUSTABLE SHOE FORM

Alfred G. Legge, Brockton, Mass.

Application August 1, 1934, Serial No. 737,940

5 Claims. (Cl. 12—128.2)

This invention relates to shoe forms adapted to be placed in shoes to maintain them in their proper shape for display purposes or when not being worn. Such a form usually comprises a toe part connected to a heel part. In many forms of this general type, the toe part is adjustably connected to the heel part so that the length of the form may be adjusted properly which it is to spect to the length of the shoe in which it is to be used. One object of the present invention to provide a simple connection for the toe and heel parts of a form which may be conveniently adjusted.

Another object of the invention is the provision of an adjustable connection for the toe and heel parts of a form which is constructed so as to permit the form to be readily and conveniently inserted in a shoe and withdrawn therefrom without necessarily disturbing the desired adjustment.

The invention will be more clearly understood from the following description in conjunction with the accompanying drawing: in which,

Fig. 1 is a plan view of a form embodying the invention;

Fig. 2 is a longitudinal sectional view of a shoe having positioned therein a form embodying the invention;

Fig. 3 is a fragmentary elevational view of a portion of the form illustrating the operation of adjusting the form; and

Fig. 4 is a sectional view taken upon the line 4—4 of Fig. 2.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

The form illustrated in the accompanying drawing comprises a toe part 10 adapted to fit snugly in the toe portion of a shoe 11. The toe part 10 of the form may be constructed as a single integral unit, but as illustrated, comprises complementary portions 12 and 13 movable laterally with respect to one another a limited amount. The portion 13 is provided with holes 15 and 16 communicating respectively with cavities 17 and

18. Screws 19 and 20 pass through the holes 15 and 16 respectively and engage the portion 12. The heads 21 and 22 of the screws 19 and 20 respectively are positioned in the recesses 11 and 18 and are adapted to engage the bottom thereof. A leaf spring 24 is positioned between the portions 12 and 13 and is provided near its ends with elongated slots 25 and 26 adapted to receive the screws 19 and 20. The spring 24 is bowed so that its ends engage the portion 12 and its intermediate portion engages the portion 13 thereby tending to hold the portions 12 and 13 apart.

A heel part 28 is provided at one end with a block 29 adapted to engage the heel portion of the upper of the shoe 11 and is adjustably connected at its other end to an intermediate part 30 which is pivotally connected to the screw 20. A U-shaped member 31 straddles the intermediate part 30 and is movable longitudinally relative thereto. The member 31 is provided with a projection 32 adapted to enter a longitudinally extending slot 33 in the intermediate part 30 and engage the recesses 34 formed in the surface defining one longitudinal edge of the slot 33. A pin 35, which may form part of a handle 36, is carried by the member 31 and extends through the slot 33. A leaf spring 38, which is secured at one end to the forward end of the portion of the member 31 above the intermediate member 30, is provided with a downwardly offset portion 40 adapted to engage the top edge of the member 30 and normally hold the projection 32 in one of the recesses 34. The forward end of the heel part 28 extends into the U-shaped member 31 and is pivotally carried by the pin 35.

To adjust the form, the rear end of the member 31 is depressed against the action of the spring 38 to cause the member 31 to pivot about the axis of the pin 35 to raise the projection 32 out of the recess 34 and into the slot 33. When the member 31 is in this position it may be moved longitudinally forward or rearward to bring the projection 32 above another one of the recesses 34. Upon releasing the rear end of the member 31, the projection 32 will be forced into the last mentioned recess 34 by the action of the spring 38. The form may be readily removed from a shoe by inserting one's finger into the handle 36 and lifting upward, thereby causing the intermediate part 30 to swing upward about the screw 20 and draw the block 29 of the heel part 28 forward. The heel part may now be lifted out of the shoe and thereafter the toe part 10

10 may be readily withdrawn. To insert the form in a shoe these operations are reversed.

I claim:

1. A shoe form comprising a toe part, a heel part connected to said toe part, said heel part comprising two portions one of which has a longitudinal slot and spaced recesses in the surface defining one edge of the slot, and means for connecting said portions including a longitudinally movable member having a projection adapted to extend into said slot and recesses, and a spring interposed between said member and one of said portions tending to maintain said projection in engagement with one of said recesses.
- 15 2. A shoe form comprising a toe part, a heel part pivotally connected to said toe part, said heel part comprising two portions one of which has a longitudinal slot and spaced recesses in the surface defining one edge of the slot, and means for connecting said portions including a longitudinally movable member having a projection adapted to extend into said slot and recesses, and a spring interposed between said member and one of said portions tending to maintain said projection in engagement with one of said recesses.
- 20 3. A shoe form comprising a toe part, a heel part connected to said toe part, said heel part comprising two portions one of which has a longitudinal slot and spaced recesses in the surface defining one edge of the slot, and means for connecting said portions including a longitudinally movable member having a projection adapted to extend into said slot and recesses, and a spring interposed between said member and one of said portions tending to maintain said projection in engagement with one of said recesses.
- 25 4. A shoe form comprising a toe part, a heel part pivotally connected to said toe part, said heel part comprising two portions one of which has a longitudinal slot and spaced recesses in the surface defining one edge of the slot, and means for connecting said portions including a longitudinally movable member carrying a pin extending into said slot, said member having a projection adapted to extend into said slot and recesses, and a spring interposed between said member and one of said portions tending to maintain said projection in engagement with one of said recesses.

5 said slot, said member having a projection adapted to extend into said slot and recesses, and a spring interposed between said member and one of said portions tending to maintain said projection in engagement with one of said recesses.

4. A shoe form comprising a toe part, a heel part pivotally connected to said toe part, said heel part comprising two portions one of which has a longitudinal slot and spaced recesses in the surface defining one edge of the slot, and means for connecting said portions including a longitudinally movable member carrying a pin extending into said slot, said member having a projection adapted to extend into said slot and recesses, and a spring interposed between said member and one of said portions tending to maintain said projection in engagement with one of said recesses.

5. A shoe form comprising a toe part, a heel part connected to said toe part, said heel part comprising two portions one of which has a longitudinal slot and spaced recesses in the surface defining one edge of the slot, and means for connecting said portions including a longitudinally movable member carrying a pin extending into said slot, said member having a projection adapted to extend into said slot and recesses, and a spring interposed between said member and one of said portions tending to maintain said projection in engagement with one of said recesses.
